UNITED STATES PATENT OFFICE.

LOUIS THEILER, OF SPIRIT FALLS, WISCONSIN.

POISON CONTAINER.

Application filed August 20, 1924. Serial No. 733,237.

This invention relates to improvements in containers and has for its principal object to provide a means whereby the accidental and unintentional use of poisons in bottles can be effectually prevented.

Another important object of the invention is to provide a poison container of the above mentioned character, wherein the mouth of the bottle has extending upwardly therefrom a plurality of tines which will prevent the mouth of a person from being placed over the mouth of the bottle in order to prevent a person from drinking poisonous contents of the bottle.

A further object of the invention is to provide a poison container of the above mentioned character, which is provided with sharpened spurs so as to prevent a person from accidentally and unintentionally using the container in which the poison is placed, the spurs providing an indicating means of the contents of the bottle or container which has been accidentally grasped.

A further object of the invention is to provide a poison container of the above mentioned character, which is simple in construction, inexpensive, strong and durable and furthermore adapted for the purposes for which it is designated.

Other objects and advantages of this invention will become apparent during the course of the following description.

In the accompanying drawing forming a part of this specification and in which like numerals designate like parts throughout the same:

Figure 1 is a side elevation of the poison container embodying the present invention.

Figure 2 is an end elevation thereof, and

Figure 3 is a top plan view of the same.

In the drawing wherein for the purpose of illustration is shown the preferred embodiment of my invention, the numeral 1 designates a poison container which in the present instance is a bottle, the same being substantially rectangular in design the mouth of the bottle being designated by the numeral 2. Extending laterally from the side and ends of the bottle are the diamond shaped spurs 3, any number of these spurs may be provided as is desired and further are so arranged as to prevent a person from grasping the bottle without coming in contact with the spurs.

For the purpose of preventing a person from placing his mouth over the mouth

of the bottle in attempting to drink the poisonous contents of the same, I have provided the upwardly diverging relatively elongated tines 4 which extend upwardly from the mouth of the bottle 2 in the manner clearly illustrated in the drawing. The usual stopper 5 is adapted to be inserted into the top of the mouth of the bottle in the usual manner without the person's fingers coming in contact with sharpened tines which extend upwardly from the mouth of the poison container.

In order to pour the contents of the poison container whenever it becomes necessary to use the poison for the proper medicinal purposes, the mouth of the bottle is provided with a pouring lip 6, such as is clearly illustrated in the drawing.

If desired, a metal jacket having spurs extending laterally from the body thereof and also spurs extending upwardly from the upper portion thereof which fits over the mouth of the bottle may be placed over a bottle of the usual construction and in which a poison is contained for carrying out the purposes of the present invention.

It will thus be seen from the foregoing description, that a poison receptacle has been provided wherein the mouth of a person will be prevented from coming in contact with the mouth of a bottle in an attempt to drink the poisonous contents thereof. Furthermore, the provision of the spurs on the mouth of the bottle will at once indicate to the person grasping a bottle that contains a poisonous liquid or solid substance effectually preventing any accidental or unintentional use of the poison in the container.

While I have shown the preferred embodiment of my invention, it is to be understood that various changes in the size, shape and arrangement of parts may be resorted to without departing from the spirit of the invention and scope of the appended claims.

Having thus described the invention, what I claim is:

1. A poison container comprising a bottle having means formed integral with the mouth of the neck thereof to prevent drinking of poison contained in the bottle, said means comprising a plurality of relatively long sharpened tines disposed in circumferentially spaced relation and diverging upwardly.

2. A poison container comprising a bot-

tle having means formed integral with the mouth of the neck thereof to prevent drinking of poison contained in the bottle, said means comprising a plurality of relatively long sharpened tines disposed in circumferentially spaced relation and diverging upwardly, and a web formed between an adjacent pair of tines, said web having a depressed groove, whereby to provide a discharge spout. In testimony whereof I affix my signature.

LOUIS THEILER.
